F. L. BRONSON

MOP

Filed May 18, 1923

UNITED STATES PATENT OFFICE.

FRED L. BRONSON, OF WICHITA FALLS, TEXAS.

MOP.

Application filed May 18, 1923. Serial No. 639,857.

To all whom it may concern:

Be it known that I, FRED L. BRONSON, a citizen of the United States, residing at Wichita Falls, in the county of Wichita and 5 State of Texas, have invented certain new and useful Improvements in Mops; and I do hereby declare the following to be a full, clear, and exact description of the invention, such as will enable others skilled in the art 10 to which it appertains to make and use the same.

This invention relates to a mop or swab and has for its object the provision of an article of the nature stated which is admirably adapted for dusting, polishing and 15 cleaning waxed floors and other surfaces without marring the same and which admits of pressure being exerted when necessary without bringing any unyielding part of the 20 mop head in contact with the surface which may tend to scar or otherwise disfigure the same.

A further object of the invention is the provision of a mop head of foliate outline 25 having a shank of corresponding configuration centrally disposed and adapted to have a handle adjustably fitted thereto, whereby to present any foil or cusp and equalize the wear on the mop or swab.

30 Other objects and advantages will be apparent and suggest themselves as the nature of the invention is understood.

While the drawings illustrate an embodiment of the invention it is to be understood 35 that in adapting the same to meet different conditions and requirements, various changes in the form, proportion and minor details of construction may be resorted to without departing from the nature of the invention.

40 Referring to the accompanying drawings forming a part of the application:

Figure 1 is a top plan view of a mop head embodying the invention, the dotted lines 45 showing an adjusted position of the handle and the full lines showing a portion of the mop or swab in engagement with an end portion of the frame,

Figure 2 is an edge view of the mop, the 50 outer portion of the handle being broken away,

Figure 3 is a detail sectional view on the line 3—3 of Figure 1,

Figure 4 is a detail view showing the 55 meeting ends of the wire from which the

mop head is formed, and Figure 5 is a sectional view of the frame taken on a plane indicated by the line 5—5 of Figure 1, looking in the direction of the arrow.

Corresponding and like parts are referred to in the following description and designated in the several views of the drawings by like reference characters.

The mop head is preferably formed from stout wire which is bent into the shape substantially as shown, whereby to form a frame and a shank, the frame being preferably of foliate form and the shank of corresponding outline and centrally disposed.

In the preferable construction, the mop head 70 is trefoil shape and comprises a frame 1, a shank 2 and a stem 3. These parts consist of a single stout wire bent into the shape substantially as outlined, the meeting ends of the wire overlapping, as indicated at 4 in Figure 4, whereby to maintain the ends in alignment and provide for a mutual spacing.

The frame 1 is of trefoil outline and all the cusps or foils are in the same plane. The shank 2 is centrally disposed and is of triangular form with its angles opposite the cusps or foils of the frame. The shank 2 is in a higher plane than the frame 1 and is connected to the latter by means of the stem, 75 80

3 which extends inwardly from a side of the frame 1 with its inner end bent upwardly and terminating in the shank 2. The side elements comprising the stem 3 are spaced apart and receive a portion of the mop or swab, thereby admitting of pressure 85 being applied to the handle without causing any part of the mop head to come in contact with the surface and mar or otherwise disfigure the same. The inner ends of the side elements of the stem 3 are bent together, as shown most clearly in Figures 1 and 2, for a mutual bracing action. The 90

sides of the shank 2 come opposite the sides of the frame 1 and are straight to admit of pivotal adjustment of the handle when 100 clamped thereon in an adjusted position. The inwardly curved sides of the frame 1 result in a prominent outline of the cusps or foils 5 of the frame 1 and further function to prevent creeping or displacement of the mop or swab after the same has been threaded upon the frame and stem.

The mop or swab 6 is of the usual and well known fringed formation having a hem or tuck 7 along an edge which receives the 105 110

frame and stem of the mop head. The mop or swab, when applied to the mop head, engages the frame and stem, these parts being received in the hem or tuck 7.

5. The handle 8 is provided at its inner or attaching end with a clamp comprising similar sections 9 having jaws 10 and fitted against opposite sides of the handle and secured thereto by means of a bolt 11, a side 10 of the shank 2 being gripped between the jaws 10. Upon loosening the bolt 11, the handle may be fitted to any side of the shank 2 and at any relative angle and is held fast in the adjusted position by retightening the 15 bolt 11.

It will be understood from the foregoing, taken in connection with the accompanying drawings, that the invention results in the provision of a mop in which the handle may 20 be attached so as to present any selected point of the mop forwardly to receive the wear, the adjustment admitting of equalizing the wear upon the mop or swab. Moreover, by having the handle attached centrally 25 to the mop head, the pressure applied thereto is equalized upon the mop and by having the stem 3 carrying a portion of the mop or swab, contact thereof with the surface is prevented and in consequence considerable 30 pressure may be applied to the handle without fear of marring or disfiguring the surface by any part of the mop head being caused to come in contact therewith.

What is claimed is:

35 1. In a mop, a head comprising a frame of foliate outline and having the sides inwardly curved to prevent creeping or displacement of the mop and to prominently display foils or cusps, a shank of polygonal 40 outline centrally disposed relatively to said head, a handle attachable to any side of the

shank, and a mop having a hem or tuck for the reception of the frame.

2. In a mop, a head comprising a frame of foliate outline, a centrally disposed shank 45 of polygonal outline having its sides and angles opposite the respective sides and foils of the frame, and a stem forming connecting means between the frame and shank, a mop on the frame, and a handle adapted to 50 be attached to any side of the shank, whereby to bring different portions of the mop in forward position.

3. A mop comprising a frame of trefoil outline, a centrally disposed triangular 55 shank having its angles and sides opposite the respective foils and sides of the frame, a stem forming connecting means between the shank and frame and comprising spaced elements, a mop fabric mounted upon the 60 frame and the spaced elements of the stem, and a handle adapted to be attached to any side of the shank to bring any required point of the frame in forward position.

4. A mop comprising a head including a 65 frame, shank and stem forming parts of a single wire, the meeting ends of which are overlapped, said frame being of trefoil outline, the shank being elevated, centrally disposed and of triangular form and arranged 70 with its angles and sides opposite the respective foils and sides of the frame, and the stem comprising spaced side elements with their inner ends brought together and upwardly bent, a mop fabric threaded upon the 75 frame and spaced elements of the stem, and a handle adapted to be attached to any side of the shank to bring any required point of the mop in forward position.

In testimony whereof I affix my signature.

FRED L. BRONSON.
